STADIUM SEAT

Reno P. Eppink, Whittier, Calif.
(11900 Center St., Hollydale, Calif.)

Filed June 24, 1960, Ser. No. 61,105

Term of patent 14 years

(Cl. D15—8)

Fig. 1.

Fig. 2.

Figure 1 is a front pictorial view of a stadium seat incorporating my new design; and

Fig. 2 is a rear pictorial view thereof.

The dominant feature of my design resides in the shape and proportions of the stanchions above their brackets and the overall contour of the seat and back in relationship to the stanchions.

I claim:

The ornamental design for a stadium seat, substantially as shown and described.
